(57) **CLAIM**

The ornamental design for push-on screwless wall plate and guide light, as shown and described.

DESCRIPTION

FIG. 1 is a front perspective view of the push-on screwless wall plate and guide light showing the new design; FIG. 2 is a close-up perspective view of an inside of a tab member shown in FIG. 1;

FIG. 3 is a front view of the design shown in FIG. 1;

FIG. 4 is a right side view of the design shown in FIG. 1;

FIG. 5 is a close up perspective view of one side of the tab member shown in FIG. 4;

FIG. 6 is a close up view of the side of the tab member shown in FIG. 4;

FIG. 7 is a left side view of the design shown in FIG. 1; FIG. 8 is a close up perspective view of the tab member shown in FIG. 7;

FIG. 9 is a close up front view of the tab member shown in FIG. 7;

FIG. 10 is a top view of the design shown in FIG. 1; FIG. 11 is a close up view of the tab recess member shown in FIG. 10;

FIG. 12 is a close up perspective view of the tab recess member shown in FIG. 10;

FIG. 13 is a bottom view of the design shown in FIG. 1;

FIG. 14 is a rear view of the design shown in FIG. 1;

FIG. 15 is a close up perspective view of the side tab member shown in FIG. 14; and

FIG. 16 is a close up view of an attachment member shown in FIG. 14.

FIG. 17 is a front perspective view of a second embodiment of the push-on screwless wall plate and guide light showing the new design;

FIG. 18 is a close-up perspective view of an inside of a tab member shown in FIG. 17;

FIG. 19 is a front view of the design shown in FIG. 17;

FIG. 20 is a right side view of the design shown in FIG. 17;

FIG. 21 is a close up perspective view of one side of the tab member shown in FIG. 20;

FIG. 22 is a close up view of the side of the tab member shown in FIG. 20;

FIG. 23 is a left side view of the design shown in FIG. 17;

FIG. 24 is a close up perspective view of the tab member shown in FIG. 23;

FIG. 25 is a close up front view of the tab member shown in FIG. 23;

FIG. 26 is a top view of the design shown in FIG. 17;

FIG. 27 is a close up view of the tab recess member shown in FIG. 26;

FIG. 28 is a close up perspective view of the tab recess member shown in FIG. 26;

FIG. 29 is a bottom view of the design shown in FIG. 17;

FIG. 30 is a rear view of the design shown in FIG. 17;

FIG. 31 is a close up perspective view of the side tab member shown in FIG. 30; and,

(Continued)

FIG. 32 is a close up view of an attachment member shown in FIG. 30.
The circular broken lines and arrows showing the enlarged areas of the claim form no part of the claimed design.
